UNITED STATES PATENT OFFICE

JAMES F. BRADLEY, OF STAFFORD SPRINGS, CONNECTICUT, ASSIGNOR OF ONE-HALF
TO VICTOR J. BISSONNETTE, OF STAFFORD SPRINGS, CONNECTICUT

RUBBER HEEL

Application filed June 12, 1930. Serial No. 460,635.

This invention has to do broadly with heel constructions used in footwear, and is more particularly concerned with a novel type of heel including means for detachably fastening it to the heel portion of the sole.

The invention has in view, as an important object, the provision of heels, particularly composition heels such as rubber heels, with which are associated means for detachably affixing them to the heel portion of the sole. This feature of detachability of the heels has the advantage of permitting the wearer of a pair of shoes to interchange the heels of one shoe with those of the other, whereby the heels would be worn down in an even manner, which is to be contrasted to the very common condition of heels becoming worn more on one side than on the other.

In carrying out the above noted thought in a practical embodiment, certain conditions arise which must be taken care of in order to provide a product which might prove commercially successful. In the first place, it is necessary to provide good anchorage means for the detachable connection in the rubber heel. The latter is of a material which is necessarily resilient and yielding, and which does not readily lend itself to the thought of detachably connecting it to the heel portion of the sole.

In accordance with this invention, a metallic plate is embedded in the rubber heel in a novel manner, and this plate is availed of as a sort of anchoring plate for the detachable connection. A particular feature of the invention is associated with the manner in which the plate is embedded in the rubber heel. The edges of the former are serrated, while the body portion is perforated so that the material of the rubber heel will extend through the perforations and into the serrations, whereby the plate is thoroughly embedded in the heel and rigidly held in position therein. The edges of the plate, preferably, stop short of the periphery of the rubber heel. Inasmuch as quick detachability necessarily implies the use of a very few connecting members, I propose to avail of only

two screw members for establishing the connection between the heel and the heel portion of the sole. Associated with these two screw members is a metallic plate which projects upwardly from the heel portion of the sole, and which is received in a rubber recess in the heel. Screw members extend through openings in the metallic plate embedded in the heel and have their ends threaded in the upraised plate on the leather heel portion of the sole.

Other objects will be in part obvious and in part pointed out more in detail hereinafter.

The invention accordingly consists in the features of construction, combination of elements and arrangement of parts which will be exemplified in the construction hereinafter set forth and the scope of the application of which will be indicated in the appended claim.

For a full and more complete understanding of the invention, reference may be had to the following description and accompanying drawings, wherein:

Figure 1 is a perspective view developing a shoe with my novel heel applied thereto. In this view certain parts are broken away and shown in section, to more clearly bring out the detailed construction of the heel.

Figure 2 is a section through the heel, and is taken about on the plane represented by the line 2-2 of Figure 5.

Figure 3 is a horizontal section through one of the novel heels, and is taken about on the plane represented by the line 3-3 of Figure 2.

Figure 4 is a section taken about on the same plane as the showing of Figure 2, and showing the heel as connected to the leather heel portion of the sole.

Figure 5 is a plan view of the rubber heel, and

Figure 6 is a bottom plan view of the rear portion of a shoe, with the heel omitted.

Referring now to the drawings, a conventional piece of footwear, such as a man's shoe, is designated A. The rear or heel portion of this shoe may include a leather member referred to as 10. While the rubber heel

is here described as being associated with the leather heel portion 10 of the sole, it is to be clearly understood that the latter may be omitted, although it is conventional practice in this art to include such a lift in shoe constructions.

A metallic plate 11 may be of any preferred shape, but in the illustrated embodiment takes the form shown in Figure 6. 10 It is fastened to the exposed surface of the heel 10 in any preferred manner, such as by the pegs, as shown at 12.

A rubber heel is referred to as 13, and 15 may be of any suitable rubber composition. It is also to be understood that while the present invention is described as being peculiarly adapted for use with rubber heels, it is also susceptible of use with leather heels. The same advantages attending 20 detachable heels are exhibited when this feature is availed of in conjunction with leather heels, as well as when used in association with rubber heels. However, the use of the latter is becoming more widespread than is 25 the use of leather heels, and the invention is accordingly here described as being associated with a rubber heel. Embedded in the rubber heel 13 is a metallic plate 14, having a serrated edge indicated at 15. The latter edge stops short a slight distance, say about 30 one-eighth of an inch, from the periphery of the rubber heel 13, and the material of the latter extends into the serrations of the serrated edge. The plate 14 may also be 35 provided with a plurality of openings or perforations 16, through which the material of the rubber heel also extends. The arrangement of the serrations 15 and the openings 16 provides for a rigid and positive 40 anchoring of the metal plate 14 in the rubber heel 13. This metallic plate 14 is also provided with a pair of openings 17 for a purpose to be hereinafter described.

The heel 13 is provided with a recess designated 18 which is complementary to the metallic plate 11, and is designed to receive the latter. The bottom of this recess may be defined by the rubber material of the heel in a construction such as shown in Figure 2, or it may be defined by the metallic plate 14, as shown in Figure 4.

The metallic plate 11 is also provided with a pair of threaded openings 19 which are opposite the openings 17 in the plate 14 55 when the heel 13 is positioned on the heel 10, with the plate 11 fitting into the recess 18. A pair of screw members designated 20 extend through the openings 17, and have their ends threaded into the openings 60 19 to establish the connection between the heel 13 and the heel 10. Interposed between the heads 21 of the screw members 20 and the metallic plate 14 there may be positioned 65 spring washers 22, shown in Figure 2. These spring washers serve as a sort of lock

means for preventing rotation of the screw members 20 to insure against accidental unscrewing of these screw members 20. As shown in the drawings, the rubber heels 13 are provided with a pair of openings 23 which receive the washers 22 and the screw members 20. This arrangement provides for a good bearing of the heads of the screw members against the metallic plate, at the same time countersinking the latter beneath the wearing surface of the rubber heels. 70 75

In attaching a heel such as above described to a shoe, all that is necessary to do is to place the heel 13 on the heel 10, with the metallic plate 19 received in the recess 18. Two screw members 20 are then threaded into the plate 11, with the heads 21 tightly clamped against the washers 22, whereby a rigid and positive connection of the heel is insured. When it is desired to interchange the heel on the right shoe with the heel on the left shoe of a pair, the heels may be quickly detached for this purpose by unscrewing the screw members 20 and positioning them on the proper shoes, as 80 85 above described. The detachable heel of the present invention is also adapted to be secured to the lift of a shoe.

It is evident that in the foregoing construction simplicity as to design, as well as 90 detaching and attaching operations, has been attained to a very high degree. Moreover, the heel construction is easily manufactured and susceptible for use with a conventional type of shoe now on the market 95 or in use by the public. All that is necessary to use my invention is to apply one of the metallic plates to the heel portion of a sole, whereupon the invention may be practiced as herein described. 100 105

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claim is intended to cover all of the generic and specific features of the invention herein described and all statements of the scope of the invention which, as a matter of language, might be said to fall therebetween. 110 115 120

What is claimed is:

In a heel construction for a shoe, a detachable heel; a plate embedded in said detachable heel and having a portion of its upper surface exposed, a flat plate secured to the shoe and contacting with the exposed surface of the first plate when the detachable heel is in place on the shoe, said first plate having openings therein, said flat plate 125 130

having screw threaded openings therein lying within the flat surfaces of the flat plate, and screw members passing through the openings in the first plate and threaded into the openings in the flat plate but terminating substantially flush with the inner surface of the flat plate.

5 JAMES F. BRADLEY.
